UNITED STATES PATENT OFFICE.

WILLIAM A. LOTZ, OF NEWARK, NEW JERSEY, ASSIGNOR TO THE T & L CO., INC., OF NEWARK, NEW JERSEY, A CORPORATION OF NEW JERSEY.

BAG-HANDLE CONNECTION.

Application filed January 31, 1924. Serial No. 689,792.

This invention relates to improvements in means for attaching bag handles to their frames and has as its main object to provide an essentially simple device for accomplishing this result, the same being pleasing in appearance and of broad general application.

Another aim is in the provision of a carrying handle attaching means, comprised of only two parts, inexpensive to manufacture, easy to apply and which is not readily liable to derangement in use.

These several aims and objects are attained by the novel design, construction and arrangement of parts hereinafter described and shown in the accompanying drawing, forming an essential part of this disclosure, and in which:

Figure 1 is a perspective view of an embodiment of the invention illustrating its application to a fragment of a conventional bag.

Figure 2 is a longitudinal sectional view of the fastener, taken on the center of the same, shown as applied.

Figure 3 is a transverse sectional view of the same, the section being taken on line 3-3 of Fig. 2.

Figure 4 is a perspective view of the fixed or permanently applied bracket element looking from the lower side.

Figure 5 is a side view of the handle engaging loop prior to engagement in the bracket.

Figure 6 is a fragmentary view of the same showing a minor modification.

Throughout the several views the numeral 10 is used to designate an element easily recognizable as an ordinary commercial carrying handle, such as is commonly used in connection with bags, valises and like hand baggage, the same being engaged in some manner with one of the members 11 of a frame here shown conventionally, and to which the bag body is secured.

In the present instance the frame is pierced to produce narrow transverse slots 12, at about the center of its width and suitably spaced to receive the fastening elements of the brackets by which the handle 10 is secured.

These brackets, designated generally by the numeral 13, are obviously used in pairs, and consist of a flat rectangular plate 14 of appropriate dimension, having a central

transverse, raised portion 15, its curved contour blending neatly into the smooth surface of the flat portions of the plate.

The plate edges are flanged downwardly on opposite sides of the element 15, to present side and end walls, respectively 16 and 17, the latter having central extensions 18, which may terminate preferably in points as shown, and which are proportioned and adapted to enter the frame slots 12 and be bent tightly against the inner surface of the frame, clinching the bracket firmly thereon.

The side walls 16 contain open recesses 19 having parallel edges and concavely curved bottoms as indicated, these recesses extending into the sides to points equivalent to the axis of the curved raised elements 15, all of these elements being of unitary construction, being struck in dies from a single piece of sheet metal.

The handle loops or eyes 20 are made from wire of suitable diameter, the blank being shown in Fig. 5, in which it will be seen that the registering ends 21 are suited to be engaged in the recesses 19 and have extending from them convergingly curved elements 22, joined by a somewhat flattened arc 23.

In the modification illustrated in Fig. 6, at the intersection of the ends 21 and side elements 22, a groove 24 is made, the same being suited to engage the edges of the recesses 19, this arrangement avoiding any possibility of displacement of parts.

In assembling, the loop is passed through the opening provided for it in the end of the handle 10 and thereafter the end elements 21 engaged in the recesses 19 of the bracket, at that time firmly secured on the bag frame.

Pressure is brought to bear on the outer sides of the elements 22, causing the ends 21 to turn upward, as seen in Figures 2 and 3, clinching the loop within the bracket but permitting it to turn freely, the extreme ends of the elements 21 clearing the interior of the central raised portion 15 of the bracket in whatever angular position the loop may assume relative to it, and it may be further pointed out that closing the loop side inwardly, causes the flattened portion 23 to assume its proper curvature.

Although I have described my improvements with considerable detail and with respect to certain particular forms of my invention, I do not desire to be limited to such

details since many changes and modifications may well be made without departing from the spirit and scope of my invention in its broadest aspect.

5 Having thus described my invention, what I claim as new and desire to secure by Letters Patent, is:—

- 10 1. A bag frame handle connection comprising a bracket formed of sheet metal in the shape of an oblong rectangle having a curved centrally raised transverse portion, flanged side and end walls formed on said plate, said side walls having open recesses extending into the raised portion, prongs on the end walls suited to engage openings in the bag frame and be clinched thereto, and wire loops engageable with the handle, the ends of said loops being inturned to engage in the mentioned recesses and upturned 15 within the raised portion of said bracket
- 15
- 20

clear of the upper wall thereof whereby the loops are seated in the recesses and prevented from spreading.

2. A bag frame handle connection comprising a hollow bracket having an arcuately raised, transverse central portion, means integral with the bracket for securing it to the bag frame, a curved wire loop engaging the bag handle, the ends of said loop being pivotally inturned and having recesses at 30 their inner angles adapted to engage in the edge of the bracket recesses to pivot therein, said loop ends being bent to extend angularly into the space below the raised portion of said bracket and clearing the upper wall 35 thereof.

This specification signed and witnessed this 24th day of January, 1924.

WILLIAM A. LOTZ.
